UNITED STATES PATENT OFFICE.

MARGARET M. WILLIAMS, OF CAMPBELL, CALIFORNIA.

DESIGN FOR A HAT.

Application filed November 29, 1922. Serial No. 4,448. Term of patent 3½ years.

To all whom it may concern:

Be it known that I, MARGARET M. WILLIAMS, a citizen of the United States, residing in the city of Campbell, county of Santa Clara, and State of California, have invented a new, original, and ornamental Design for a Hat, of which the following is a specification, reference being had to the accompanying drawing, forming part thereof.

Fig. 1 is a top view of the hat.

Fig. 2 is a perspective view of same.

I claim:

The ornamental design for a hat as shown.

MARGARET M. WILLIAMS.

Witnesses:

R. G. ARCHIBALD,
ANNA E. HAGELIN.
